UNITED STATES PATENT OFFICE.

HOWARD F. SNYDER, OF NEWTON, IOWA, ASSIGNOR TO THE MAYTAG COMPANY, OF NEWTON, IOWA, A CORPORATION OF IOWA.

SAFETY DEVICE FOR WRINGERS.

Application filed July 14, 1921. Serial No. 484,681.

To all whom it may concern:

Be it known that I, HOWARD F. SNYDER, a citizen of the United States, residing at Newton, in the county of Jasper and State 5 of Iowa, have invented certain new and useful Improvements in Safety Devices for Wringer, of which the following is a specification.

This invention relates to clothes wringers, 10 and more particularly to the provision of a safety device, and means for feeding the clothes to the rolls. Among the objects of my invention are to provide in clothes wringers a safety device to eliminate the 15 danger of the operator getting his fingers caught between the rolls; further the provision of a manually operated attachment for wringer rolls in the form of a fabric guide having, preferably, a pivotal connection with the wringer frame so that the 20 guide can be manually shifted from and toward the bite of the rolls and instantly withdrawn in case of over-feeding, in which the guide is adapted in inward position to 25 project into the space between the peripheries of the rolls opposite the bite thereof and preferably substantially into contact with a roll, and no closer, whereby to cause the fabric to be grabbed by the rolls without drawing the guide along with it; further 30 the provision of such a device which is constructed and arranged to be quickly attached to either side of the wringer rolls; further in the provision of fabric guiding 35 means adapted to automatically return to its normal position removed from the rolls after the fabrics have passed therefrom to the wringer so as to be in position to receive a new batch; further in the provision of a 40 guiding means adapted to be held in operative position adjacent the bite of the rolls due to the dragging of the fabrics passing over the guiding means as they are passing through the rolls; further in providing 45 fabric guiding or supporting means constructed and arranged to be positioned adjacent the bite between the rolls to feed the fabrics thereto and to be shifted to a position removed therefrom to receive a 50 fresh supply of fabrics, said guiding means being adapted to substantially shield the bite of the rolls when in fabric receiving position; further the provision of means for correctly feeding the clothes into the rolls 55 and preventing the same from becoming

wrapped around the rolls; further to prevent buttons from tearing off or becoming broken while the article carrying the same is being fed through the wringer; further to provide a safety device of improved construction, and one that can be readily transferred from one side of the machine to the other; further to produce a safety device of maximum simplicity, efficiency, economy and ease of operation; and such further objects, 60 65 advantages and capabilities as will later more fully appear.

My invention further resides in the combination, construction and arrangement of parts illustrated in the accompanying drawings, and while I have shown therein a preferred embodiment I desire it to be understood that the same is susceptible of modification and change, without departing 70 75 from the spirit of my invention.

In the drawings:—

Fig. 1 is a side elevation of a wringer having my improved safety device attached thereto.

Fig. 2 is a vertical transverse section on 80 a line 2—2 of Fig. 1.

Fig. 3 is a perspective view looking toward the under side of the safety device.

Referring to the drawings, my improved safety device is designated generally at A, and comprises the clothes support or guiding means 1, which at its upper forward side when in the position shown in Figs. 1 and 2, is preferably flat, as shown at 2, which flat portion merges into the downwardly and outwardly curved face 3, terminating in the lower edge 4. Fixed adjacent the respective ends of support or guide 1, are the downwardly extending brackets 5 and 6, the latter of which at its inner end 85 is formed with the opening 7, adapted to pivotally receive pin 8, carried by the side portion 9 of the wringer frame. Bracket 5 at its inner end is cut away as shown at 10, and is provided on its inner face with a resilient arm 11, fixed at its inner end to the bracket 5, and provided at its free end with an opening 12, which lies opposite the recess or notch formed by the cutaway portion 10. The opposite side portion 13 of 100 the wringer frame carries an outstanding pin 14, adapted to pass through opening 12, which in conjunction with opening 7 and pin 8 pivotally mount the safety device upon 105 the wringer frame for a purpose hereinafter 110

more fully set forth. Adjacent the end of spring arm 11, but removed a slight distance inwardly from opening 12, is a keeper 15, which overlies arm 11, and stands away 5 from bracket 5, a distance sufficient to permit arm 11 to be moved away from arm 5, far enough to clear the end of pin 14 to permit removal of safety device A from the wringer, which may be effected by first releasing the same from pin 14 in a manner 10 just described, and then withdrawing the same endwise from pin 8.

To permit use of the safety device on either side of the wringer, the corresponding side portions of the opposite side are provided with similar pins to be received in openings 7 and 12 in a manner which will be readily understood from the above.

As noted in Fig. 1, the support or guide 1 is formed at its opposite ends with the up-standing flanges 16, 17, which are inclined away from each other toward their outer edges, and which extend downwardly to edge 4. In addition, the guide 1 is provided 25 with shoulders 17' which limit the inner movement or position of the lip 18 of the guide 1 relatively to the bite of the rolls.

When in fabric feeding position as shown in Figs. 1 and 2, the tip or inner edge 18 of 30 the fabric guide 1 will lie in the space between the peripheries of the rolls opposite the bite thereof and will be substantially touching more or less or just out of contact with the lower roll 19 on a line a slight distance outwardly from the meeting line or 35 bite of the rolls.

In the operation of my improved safety device, it will normally stand away from the rolls with the lower edge of brackets 5 and 6 contacting face 21 of the drain board, or such other part of the wringer frame as may be presented in the different makes of wringers. Assuming that the article to be wrung is of fair size, it will be thrown with 45 its edge slightly across edge 18 of support or guide 1, and support or guide 1 will then be manually swung upwardly to bring it into the position shown in Fig. 2, at which time the adjacent edge of the garment will be 50 picked up by the lower roll, and immediately carried between the rolls, without the necessity of the operator's hand coming any closer to the rolls than lower edge 4 of support or guide 1, which edge he may grasp 55 in rotating the support or guide into operative position. It is of importance to note that when the edge of the garment is thrown across edge 18, it will be passed between the rolls, with its edge underlapped, which I 60 have found prevents any possibility of the garment becoming wrapped around the wringer rolls. In addition, it must be evident that by reason of the fact that the attachment is free to be manually swung away 65 from the rolls it is instantly releasable in

the event a fabric tends to choke the rolls, and further, that the shoulders 17' contact with the vertical sides of the wringer frame and thus prevent the lip from being drawn into the bite of the rolls along with the 70 fabric. Small articles, such as handkerchiefs, and the like, may be laid on to the upper surface of a larger article which is passing over the guiding means 1, and thus be carried between the rolls, without the necessity, for example, of laying the article 75 any closer to the rolls than upon curved face 3, the articles being thus carried between the rolls upon the larger article being wrung, thus again avoiding any possibility of the 80 smaller articles becoming wrapped around the wringer rolls. The outer portion 22 of the drain board on the opposite side of the machine, will serve as a guide to guide the wrung clothes into a basket, if desired, without the necessity of the operator receiving the articles in his hand from the outwardly moving side of the rolls. In passing over guiding means 1, buttons, and the like, will be caused to lie flat, and thus will go between 85 the rolls in a flat or horizontal position, thus eliminating all danger of tearing off any of the buttons, or breaking the same. Since all that is necessary after placing the edge of the article to be wrung over edge 18 of guiding means 1, is to push upwardly on lower edge 4, or grasp any other of the lower portions of the safety device desired, it will be readily seen that the fingers of the operator 90 may be kept well away from the wringer 100 rolls, and any liability of the fingers being caught therebetween will be entirely eliminated. While I have illustrated the spring arm 11 as one means for removing the safety device from pins 8 and 14, I wish it understood that other means may be used to accomplish this purpose, without departing from the spirit of my invention.

Due to the free pivotal mounting of the supporting or guiding means on the pins 14 and to the disposition of the center of weight of the guiding means to the rear of the pin 14 and the location of the presenting edge 18 adjacent the bite of the wringer cylinders, it is manifest that when the clothes and other fabrics are being pulled forwardly between the wringer rolls, as they drag over the supporting means, the dragging action will maintain the latter in the position illustrated in Fig. 2, of the drawings, and that 110 upon the completion of the feed of the fabric through the rolls, the safety device will automatically fall by gravity against drain board 21 (or 22, depending upon which side of the wringer the device is located) thus 115 presenting edge 18 in an upward position and well away from the wringer rolls to receive a further article to be wrung, which may then be passed between the rolls by merely rotating table 1 to bring edge 18 into 120 125 130

position shown in Fig. 2. It will be noted that due to the curvilinear surface of the guiding means and the disposition of its pivotal axis at 14, the upper edge 18 of the guiding means will move in a substantially arcuate path upwardly across the normal horizontal line of fabric feed into a position (when the lower end of the guide 3 contacts with drain board 21), such that the guiding means substantially shields or guards the opening between the rolls.

Having now described my invention,

I claim:

1. In a safety device for wringer rolls, a guiding means for supporting articles to be wrung and having arms at its respective ends, pivot pins on the wringer frame, said arms having openings near the free ends thereof for mounting on said pins to permit the guiding means to be swung toward or from the wringer rolls, and means adjacent the opening in one of said arms to permit easy removal of the same from its pin, so that the safety device may be transferred to the other side of the wringer, when desired.

2. In a safety device for wringers, a movable guiding means for supporting articles to be wrung and comprising a front edge adapted to receive the edge of an article to be wrung, said guiding means being movably mounted on the wringer frame to bring said front edge adjacent the line of contact of the two wringer rolls to cause feeding engagement of said articles by said rolls, and an upstanding flange on each end of said guiding means, said flanges being inclined outwardly away from each other to guide said articles between the rolls.

3. In combination, a wringer frame comprising spaced side portions, and having a pair of rolls, a pin mounted in each of said side portions and extending toward each other, a guiding means having a downwardly extending bracket adjacent each end, one of said brackets having an opening in its free end to rotatably receive its corresponding pin, the other of said brackets having a notch formed in its free end, and a keeper adjacent said notch, and a resilient arm fixed to said bracket and having in its free end an opening to fall opposite said notch, whereby the free end of said arm may be moved outwardly in the keeper beyond the end of the pin mounted in the opening in said arm to permit removal of the guiding means from the wringer frame.

4. In a device of the class described, the combination of a support, wringer rolls arranged in vertically superimposed relation thereon, a drain board beneath said rolls, a bracket pivoted on said support in front of said lower roll and substantially between said lower roll and drain board, guiding means carried by said bracket, said guiding means having a substantially arcuate fabric supporting surface constructed and arranged

to have its upper and lower ends move into substantial contact with the upper periphery of the lower roll adjacent the bite between the upper and lower rolls and with the drain board respectively.

5. A manually operated fabric feeding attachment for laundry wringer rolls, comprising in combination with a support on each side of the wringer frame, a fabric guide having a quick detachable pivotal connection whereby said guide can be readily mounted on either side of the rolls to be swung freely by hand from a position removed from said rolls to a fabric feeding position opposite the bite of the rolls and to be instantly releasable in said latter position to move away from said rolls to relieve feeding of the fabric between the rolls, said guide having a forwardly extending fabric receiving lip adapted to project into the space between the opposed peripheries of the rolls opposite the bite of the rolls and substantially into contact with a roll periphery whereby on rotation of the rolls said fabric is grabbed by said rolls and fed therebetween, said guide having means for preventing said lip from being drawn into the bite of the rolls along with said fabric.

6. The combination with wringer rolls, of a fabric receiving and supporting member mounted contiguous to said rolls so as to be movable toward and from the rolls, said member having a free and unobstructed surface on which the fabric is adapted to be positioned when said member is removed from the rolls and over which said fabric may be freely drawn during fabric feeding, said member having a projecting lip over which the fabric may be draped so that it will be movable with said member toward said rolls, and means for arresting movement of said member toward said rolls when said lip is positioned opposite the bite of the rolls, said member constituting the sole means for bringing the fabric up to the rolls and being movable towards said rolls by manual means alone.

7. In a device of the class described, the combination of a support, wringer rolls arranged in vertically superimposed relation thereon, an arcuate fabric guide pivotally mounted on said support and manually shiftable relatively to the rolls so as to be instantly releasable from a position adjacent said rolls, said guide providing a free and unobstructed surface on which said fabric is adapted to be draped when in position away from the rolls and over which said fabric will be freely dragged when drawn by the rolls, said guide having a forwardly projecting unobstructed lip over which said fabric is adapted to hang, which lip is adapted to be positioned close to the bite of the rolls and substantially touch one of said rolls, and means to positively limit the inward move-

ment of said guide and thereby the innermost position of said lip to prevent said lip from being drawn into the bite of the rolls together with the fabric during its feeding movement.

8. The combination with wringer rolls, of an arcuate fabric receiving and supporting member pivotally mounted substantially at its center of curvature and contiguous to said rolls so as to be movable toward and from the rolls, said member having a projecting lip over which the fabric may be draped so that it will be movable with said member

toward said rolls and means for arresting movement of said member toward said rolls when said lip is positioned opposite to the bite of the rolls, said member constituting the sole means for bringing the fabric up to the rolls and being movable towards said rolls by manual means alone, said member being so mounted as to automatically remove it from said rolls after the fabric is disengaged therefrom.

In witness whereof, I hereunto subscribe my name to this specification.

HOWARD F. SNYDER.
